United States Patent Office.

W. J. ARMSTRONG AND CHARLES BROWNE, OF BROOKLYN, NEW YORK.

Letters Patent No. 70,498, dated November 5, 1867.

IMPROVEMENT IN ANCHORS.

The Schedule referred to in these Letters Patent and making part of the same.

TO ALL WHOM IT MAY CONCERN:

Be it known that we, W. J. ARMSTRONG and CHARLES BROWNE, of Brooklyn, in the county of Kings, and State of New York, have invented a new and improved Self-Clearing Anchor; and we do hereby declare that the following is a full, clear, and exact description thereof, which will enable others skilled in the art to make and use the same, reference being had to the accompanying drawings, forming part of this specification.

Figure 1 is an edge view of our improved anchor, parts being broken away to show the construction.

Figure 2 is a side view of the same, parts being broken away to show the construction.

Similar letters of reference indicate corresponding parts.

Our invention has for its object to furnish an improved anchor, strong, durable, and simple in construction, and which shall be so constructed as to clear itself should it become fouled; and it consists in the construction of the crown, shank, and stock of the anchor, and in the manner in which said parts are attached to each other, as hereinafter more fully described.

A is the shank of the anchor, upon the lower end of which is formed a tenon, a' , the shoulders of which incline in each direction from the central point, as shown in fig. 2, so that the crown B of the anchor may rock upon the said tenon to enable the flukes C to take a surer hold upon the ground. The crown B is made with a slot through it to receive and fit upon the tenon a' of the shank A, the ends of said slot being inclined outward in each direction from the centre, as shown in dotted lines in fig. 2, to enable the said crown to rock upon the tenon without getting out of its proper relative position. It will be observed that when the fluke C of the anchor has hold of the ground, the edges of the crown B rest against the inclined shoulders of the shank A, and the inclined ends of the slot through the crown B rest against the edges of the tenon a' , so as to give the connection great firmness and strength. The crown B is secured in place upon the tenon a' of the shank A by the blocks D, which are riveted, welded, brazed, or otherwise securely and firmly attached to the sides of the lower end of the said tenon a' . The upper ends of the blocks D are inclined outward from their central points, as shown in fig. 2, in the same manner as the shoulders of said tenon. The stock E is made in two parts, the inner end of each part having a tenon formed upon it which passes through a mortise formed in the upper end of the shank A for its reception. The parts of the stock E are secured in place in the shank A by blocks F of the shank A for its reception. The parts of the stock E are secured in place in the shank A by blocks F riveted, welded, brazed, or otherwise securely attached to the side of the said tenons. The mortise through the upper part of the shank A is so formed, and the shoulders of the tenons and the inner ends of the blocks F are so inclined, that the outer ends of the parts of the stock may incline upward to allow the cable to slip off the stock should it become fouled, but they cannot move downward further than to be at right angles to the shank A. This construction allows the crown B and upper end of the shank A, where they are weakened by the mortises, to be made of any desired thickness, so as to be of any desired strength.

We claim as new, and desire to secure by Letters Patent—

1. Attaching the crown B to the shank A by passing a tenon formed upon the lower end of said shank through a mortise formed in the said crown, and securing them in place by blocks D firmly attached to the side of the projecting end of said tenon, substantially as herein shown and described, and for the purpose set forth.
2. Forming the stock E in two parts, and attaching them to the upper end of the shank A by passing tenons formed upon the inner ends of said parts through a mortise formed in the upper end of said shank, and securing them in place by means of blocks F firmly attached to the projecting ends of said tenons, substantially as herein shown and described, and for the purpose set forth.

The above specification of our invention signed by us this 18th day of September, 1867.

W. J. ARMSTRONG,
CHAS. BROWNE.
